MOISTURE-PROOF COVERED BAG

Application filed June 6, 1932. Serial No. 615,715.

The present invention relates to improvements in bags and more especially to those made of fiber paper and provided with a transparent moisture proof covering for the 5 packaging of coffee and other commodities and the sealing thereof from atmospheric or other deteriorating influences.

One of the primary objects of the invention is to provide a novel and improved bag 10 of this kind which can be made from sheet paper and moisture proof material formed into tubular shape and seamed longitudinally so that the seam edges of the moisture proof covering are pasted or united directly to one another, thus producing an effective moisture proof seal at the seam.

Another object is to provide a bag of this 20 kind wherein the seam edges of the paper bag and the seam edges of the covering are pasted together in a manner which avoids the presence of paste on the front of the bag and thereby enables the bag front to present a neat appearance.

A further object of the invention is to 25 provide a bag of this kind wherein the longitudinal seams of the paper bag and of the transparent moisture proof covering are located so closely to the adjacent longitudinal edge of the seam side of the bag as to enable such side of the bag to be printed 30 throughout its full width and equally close to its longitudinal edges and to enable the same printing plates used for printing ordinary bags to be used for printing the improved covered bags.

To these and other ends, the invention 35 consists in certain improvements and combinations and arrangements of parts all as will be hereinafter more fully described, the features of novelty being pointed out particularly in the claims at the end of the specification.

In the accompanying drawing:—

40 Fig. 1 is a perspective view of a bag embodying the present invention, upper portions of the bag being broken away for clearness in illustration;

45 Fig. 2 is a bottom plan view of the bag shown in Fig. 1;

Fig. 3 is a bottom plan view of the partially closed bag bottom; and

Fig. 4 is a transverse section through the bag taken on the line 4—4 in Fig. 1.

The present invention is applicable to bags 55 of different types, it being shown in the present instance applied to a bag of the so-called automatic type. The improved bag as shown comprises a bag proper 1 composed of fiber paper of any of the kinds 60 commonly used in making ordinary paper bags, a liner 2 composed of thin flexible material preferably having air and moisture proof properties, such as "Glassine" or other fiber paper treated to render it air and moisture proof, and an outer transparent and moisture proof covering 3 composed preferably of thin, flexible or foldable, transparent sheet material such as "cellophane" or 65 any of the other well-known thin, transparent, flexible sheet cellulose products obtained from viscose and having the properties of "cellophane". The bag as shown has tucks or pleats in its sides so that it may collapse 70 or expand, and the bottom of the bag is closed by bottom flaps 4 which are turned inwardly from the pleated sides of the bag and bottom flaps 5 which are turned inwardly from the front and rear of the bag 75 and are pasted to the flaps 4 and to one another, the bag bottom as shown being of a common and well-known form. The longitudinal edges of the liner 2 are overlapped 80 at one side of the bag and united in the usual way by a line of paste 6 to provide 85 a longitudinal seam.

According to the present invention, one of the longitudinal edges 7 of the fiber paper bag is extended inwardly from an adjacent longitudinal edge or corner 8 thereof and the 90 other longitudinal edge 9 of the fiber paper bag is extended across substantially the full width of the respective side of the bag to or nearly to the corner or edge 8 and it overlaps the longitudinal edge 7 preferably to a 95 somewhat greater extent than usual in the longitudinal seams of ordinary bags. One of the longitudinal edges 10 of the transparent moisture proof covering extends inwardly 100 from the edge or corner 8 a distance some-

what less than the width of the edge 7 of the paper bag 1 so that it overlaps the outer side of the edge 7 for a part only of its width, and the other longitudinal edge 11 of the transparent moisture proof covering is folded closely around and behind the longitudinal edge 9 of the paper bag so that it lies between the inturned edge 10 of the outer covering 3 and the overlapping edge 9 of the paper bag. The inturned edge 11 of the outer covering is pasted directly to the other edge 10 of the outer covering by a continuous line of paste 12 and the portion of the edge 9 of the paper bag which is exposed directly to the remainder of the width of the other longitudinal edge 7 of the paper bag is pasted directly thereto by a continuous line of paste 13.

The direct pasting together of the longitudinal or seam edges 10 and 11 of the outer transparent moisture proof covering 3 throughout the length of the bag provides an effective air and moisture proof seal at the longitudinal seam of the covering, and the direct pasting together of the seam edge 9 of the fiber paper bag to the remainder of the width of the other seam edge 7 thereof which is not covered by the seam edges of the outer covering provides maximum strength for the seam to prevent opening thereof. The pasting together of the seam edges 10 and 11 of the outer covering in the region between the seam edges 7 and 9 of the fiber paper bag confines the paste used in making these seams entirely within the seams so that the paste is not exposed on the exterior or outer sides of the bag and the bag consequently presents a neat appearance.

Furthermore, the formation of the longitudinal seams of the fiber paper bag and the outer covering in the manner described enables the seam side of the fiber paper bag to receive printed impressions which may occupy the full width of this side of the bag and it enables the same printing plates employed for printing the faces of ordinary bags to be used for printing the seam sides of the improved bags, since the seam edge 9 of the fiber paper bag extends to or substantially to the edge or corner 8 of the bag so that substantially the full width of the seam side of the paper bag is exposed continuously or without interruption to receive the printed impressions, it being possible to extend the printed impression as close to the edge or corner 8 of the bag as to the other edge or corner thereof. It will be understood of course that the printed impressions are made on the fiber paper bag 1 and that they will be exposed and clearly visible through the transparent covering 3.

The improved bag hereinbefore described may be made in different ways, but it is particularly suitable for rapid and economical manufacture on an ordinary bag making machine. In making the improved bags in that manner, the sheet of fiber paper from which

the bag proper 1 is made is printed in the usual manner in ordinary bag printing mechanism and after printing, the sheet of "cellophane" or other transparent moisture proof material to form the covering 3 is applied to the printed side of the fiber paper, it taking the place of the usual slip sheet, one edge of the transparent moisture proof material extending beyond the respective edge of the printed paper sheet to an extent corresponding to that to which the edge 11 is to be turned under the edge 9, and the sheet to form the liner 2 is fed to the opposite or unprinted face of the paper sheet, the lines of paste 6 and 13 being applied to the liner sheet and paper sheet as they advance. The three sheets are then formed into a bag tube as usual in an ordinary bag making machine, the pasted edges of the sheets being united to form the seams, and before uniting the seam edges 7 and 9 of the fiber paper strip, the edge 11 of the transparent covering sheet is turned under the edge 9 of the paper sheet and adhesive is applied to the side of the seam edge 11 which is opposite to the seam edge 10 and these edges of the covering and the seam edges 7 and 9 of the paper sheet are then united. The composite bag tube thus formed and seamed longitudinally is cut into bag lengths and the bottom of the bag closed in the usual and well-known manner. The upper and lower ends of the fiber paper bag 1 and transparent covering 3 may be pasted together by any suitable adhesive such as white ink which may be applied during the making of the bag, and the liner 2 may be pasted to the inside of the fiber paper bag 1 in the usual manner.

I claim as my invention:

1. A bag having a longitudinal seam, and a moisture proof outer covering therefor also having a longitudinal seam, an edge of the seam of the covering being turned under an edge of the seam of the bag for a portion of the width of the bag seam and being directly united to the other edge of the seam of the covering, and the edges of the bag seam being directly united for another portion of the width of the bag seam.

2. A bag having a longitudinal seam, and a moisture proof outer covering therefor also having a longitudinal seam the portions of which are directly united to one another, an edge of the seam of the covering being turned under an edge of the seam of the bag for a portion of the width of the latter seam and directly united to the other edge of the seam of the covering.

3. A bag having a longitudinal seam immediately adjacent to and extending along a longitudinal side edge thereof, the side of the bag having such seam being of substantially the full width of the bag, and a transparent moisture proof outer covering having a longitudinal seam an edge of which is

turned under the outer edge of the seam
of the bag for a portion of the width of the
bag seam and is united directly to the other
edge of the seam of the covering.

5 In testimony whereof I have hereunto set
my hand.

TRUE M. AVERY.
